UNITED STATES PATENT OFFICE.

JOHN P. NORTHEY, OF TORONTO, ONTARIO, CANADA.

KEY BOLT.

1,424,319.

Specification of Letters Patent.

Patented Aug. 1, 1922.

Application filed November 2, 1920. Serial No. 421,360.

To all whom it may concern:

Be it known that I, JOHN P. NORTHEY, of the city of Toronto, in the county of York, Province of Ontario, Canada, a subject of the King of Great Britain, have invented certain new and useful Improvements in Key Bolts, of which the following is a specification.

This invention relates to slotted bolts with which wedge keys are employed to set up the bolts. With such bolts it is found that the friction of the wedge key against the outer end of the slot tends to bend the stem of the bolt unless a suitable temporary anvil be employed to back up the outer end of the stem as the wedge is driven.

The method of driving is, however, troublesome and demands the exercise of skill and care on the part of the user, and my object is to devise effective backing means for the bolt stem which may be effectively employed by any unskilled or inexperienced person, and which is cheap enough to be allowed to remain in position after the wedge key has been driven.

I attain my object by forming a washer adapted to fit the bolt stem closely and to underlie the wedge and on this washer I form what I may term a slotted or divided anvil adapted to extend up substantially to the outer end of the bolt at each side of the slot and substantially in close contact with the stem.

The washer is constructed in detail substantially as hereinafter described and illustrated in the accompanying drawings in which

Fig. 1 is a cross section through a rail joint showing an anvil washer in position on a key bolt;

Fig. 2 a plan view of a bolt and key with a washer in position;

Fig. 3 a front view of the washer.

In the drawings like numerals of reference indicate corresponding parts in the different figures.

In Fig. 1 a key bolt is shown in position in a rail joint, 1 being the slotted bolt, 2 the

wedge key and 3 the special washer in position on the key bolt. One face of the washer 3 is suitably shaped to bear against the parts with which the bolt is used. The other face is suitably shaped to form a seat for the wedge key. An extension 4 is formed on the washer, which is adapted to contact with the stem of the bolt passing through the washer. Preferably the extension is sufficiently long to reach approximately to the outer end of the bolt when the latter is in position. This extension is divided or slotted to permit of the passage of the wedge key.

From the construction described it follows that as the wedge key is driven into position by the blows of a hammer, the washer is held tightly against the part through which the bolt passes and thus the extension 4 is held firmly in position to serve as an anvil to resist springing and bending of the stem of the bolt during the driving of the wedge key.

It will be noted that the key seat of the washer is inclined relative to the face which engages the part through which the bolt passes so that the back of the key is substantially at right angles to the axis of the bolt. The cramping action which occurs when the back of the key is inclined to the axis of the bolt, so that it first engages the outer edge of the end of the slot, is avoided. The key is thus more easily driven and with lessened tending to spring the bolt.

What I claim as my invention is:

A washer for a slotted key bolt having a key seat formed in one face and an extension from the same face divided from the seat to its outer end and adapted to be against the stem of the bolt in alignment with the slot to resist springing and bending of the stem of the bolt during the driving of the key, said seat being inclined to the axis of the bolt so that the outer edge of the wedge key employed with the bolt will lie approximately at right angles to the axis of the bolt.

Signed at Toronto, Canada, this 21st day of October, 1920.

JOHN P. NORTHEY.
